United States Patent

Des. 236,410
Patented Aug. 26, 1975

236,410

HOLDER FOR A BEVERAGE CAN OR THE LIKE

Sheldon W. Jenkins, Natick, Mass. (164 South St., South Natick, Mass. 01760), and Arnold J. Utstein, 58 Dwight St., Brookline, Mass. 02146

Filed Mar. 19, 1973, Ser. No. 342,673

Term of patent 14 years

Int. Cl. D7—99

U.S. Cl. D7—70

FIG. 1

FIG. 2

FIG. 3

FIG. 1 is a front perspective view of a holder for a beverage can or the like showing our new design.

FIG. 2 is a top plan view thereof. The bottom is substantially the same as the top.

FIG. 3 is a side elevational view thereof. The opposite side is substantially the same.

We claim:

The ornamental design for a holder for a beverage can or the like, substantially as shown and described.
